UNITED STATES PATENT OFFICE.

NATHAN T. HARMON, OF LINCOLN, NEBRASKA.

DIGGING AND ELEVATING MECHANISM.

1,188,765.

Specification of Letters Patent. Patented June 27, 1916.

Application filed November 17, 1914. Serial No. 872,615.

To all whom it may concern:

Be it known that I, NATHAN T. HARMON, a citizen of the United States, residing at Lincoln, in the county of Lancaster and State of Nebraska, have invented a new and useful Digging and Elevating Mechanism, of which the following is a specification.

The present invention relates to improvements in a digging and elevating mechanism, one object of the invention, being the provision of a mechanism of this character adapted to be used in connection with digging cylindrical holes in the ground, as for instance, fence posts and wells, there being provided a rotary auger member embodying a dirt receptacle in combination with a conveying mechanism operably connected therewith and disposed for movement into and out of the receptacle whereby the earth loosened and cut by the auger and deposited within the receptacle may be automatically removed therefrom during the rotation of the auger member.

A further object of the present invention, is the provision of a shaft carrying such auger member that is extensible, so that the length thereof may be increased as the hole is being dug.

A still further object of the invention, is the provision of a novel form of derrick by means of which the shaft and the auger and its receptacle may be properly supported during the operation thereof.

With the foregoing and other objects in view which will appear as the description proceeds, the invention resides in the combination and arrangement of parts and in the details of construction hereinafter described

and claimed, it being understood that changes in the precise embodiment of the invention herein disclosed can be made within the scope of what is claimed without departing from the spirit of the invention.

In the drawings Figure 1 is a front elevation of the complete apparatus. Fig. 2 is a rear elevation taken from the operating side thereof. Fig. 3 is a view partly in section and partly in elevation of the auger carrying shaft, the auger and its receptacle and the dirt elevating mechanism. Fig. 4 is a section taken through the receptacle and auger carrying member at right angles to that shown in Fig. 3, the elevator mechanism being shown in elevation. Fig. 5 is a cross section taken through the recep-

tacle. Fig. 6 is an enlarged detail view of the swivel connection to the auger carrying shaft. Fig. 7 is a cross section through the shaft showing the position of the gear and 60 socket carrying members of the elevating mechanism.

Referring to the drawings, the numeral 1 designates the base of the present structure, which consists of the two standards 2 and 65 the two standards 3, the upper ends of which are connected together by means of the platform 4. Connected between the two standards 2 is the cross bar 4' which has journaled therein for rotation, the 70 sleeve 5 of the bevel gear 6, said bevel gear 6 and sleeve 5 having passed therethrough, the vertical rotatory and longitudinally 75 slideable shaft 7, which is provided with a key-way 8 for engagement with the key (not shown) carried by the sleeve 5 and gear 6. By this means as the gear 6 is rotated, rotatory movement is imparted to the shaft 7.

The bevel gear 9 is in mesh with the gear 80 6 and through the shaft 10 and pulley 11 constitutes the driving means to rotate the shaft 7. A belt 12 is passed over the pulley 11, and is operated by the pulley 13 fixed upon the shaft 14 which is journaled at one 85 side of one standard 2 and the adjacent standard 3, as illustrated in Figs. 1 and 2. For operating the shaft 14 there is disposed upon one end the operating wheel 15, which in the present instance is shown as 90 a manually operated device, although it is apparent that the same may be operated mechanically through an explosion engine or other device.

Mounted for sliding movement within 95 the guide slot S formed in the inner faces of the standards 2, is a rod 16, which is connected to and carries the fixed sleeve 17, through which the shaft 7 passes, said sleeve 17 being provided with the bevel 100 pinion 18 which is thus held against rotation. This bevel gear 18 is in mesh at all times with the two bevel pinions 19 and 19' each one of which is provided with its respective sprocket 20 or 20'. These 105 pinions 19 and 19' and their sprockets are mounted for rotation upon the oppositely extending arms 21 of the sleeve 22, which is adapted to surround and be fixed to the shaft 7, so that when 110 the shaft 7 is rotated, the pinions 19 and 19' are also rotated by their engage-

ment with the fixed gear 18, the detail construction of which is illustrated in Fig. 3. Thus the two gears 19 and 19' will be rotated in opposite directions and in turn 5 operate the sprockets 20 and 20' in opposite directions.

Mounted upon the lower end of the shaft 7, is the earth engaging auger 23, while forming the bottom of the receptacle 25 and 10 also rotatable with the shaft 7, is the cutter portion 24 which constitutes an auger by means of which when the shaft 7 is rotated the receptacle 25 is also rotated as is the auger 23 and the cutter 24. Thus the dirt 15 is cut from below the receptacle 25 and enters through the spaces formed by the cutter 24 into such receptacle to there be removed as later appears.

Fixed upon the shaft 7 within the receptacle 25 is the sleeve 26, which carries the 20 two oppositely extending arms 27, there being mounted for independent rotation upon the arms 27 the two sprocket wheels 28 and 28'. These sprocket wheels 28 and 28' are 25 disposed to align with the sprockets 20 and 20' respectively, so that the two sprocket chains 29 and 29' which are aligned to engage the respective sprockets 20 and 28 and 20' and 28', will have movement imparted thereto so that the diagonally opposite strands 30 thereof will be moving in the same direction as indicated by the arrows in Figs. 3 and 4.

Carried by the respective chains 29 and 35 29' are the dirt receiving and removing pockets 30 which are adapted to be emptied after passing over the shaft 21 into the trough T, so as to be delivered away from the shaft 7. It will thus be seen that as 40 the shaft 7 is rotated, the proper action is imparted to the conveyers 29 and 29' so that the earth filling the receptacle 25 due to the cutting thereof by the cutter 24 will be removed from the receptacle 25 as 45 rapidly as the same accumulates therein. Thus as the receptacle 25 forms an auxiliary wall for the cut during the making thereof, the earth within the receptacle removed, will in the final operation leave the 50 bore clean cut from the top to the bottom.

The shaft 7 is a sectional shaft, so that as the bore is deepened, new lengths may be added thereto to any desired extent.

In order to provide a means for moving the 55 shaft 7 longitudinally either to permit the receptacle 25 to be lowered or to be elevated as desired, the upper end of the shaft 7 at 31 is reduced for fitting the sleeve 32, which is rotatably mounted thereon and constitutes 60 a swivel joint at such connection, the nuts 33 being disposed to lock the members in place so that the bail 34 which is attached to the sleeve 32 may be properly connected to

the cable 35 and thus be properly manipulated vertically relatively to the structure. 65

The cable 35 is passed over the pulley 36, which is journaled at the apex of the V-shaped member 37, whose offset ends are connected to the securing means 38 upon the upper surface of the platform 4 for swinging 70 movement so that the member 37 which with the leg 39 forms a tripod or derrick, may be collapsed when it is desired to transport the present mechanism. The upper end of the member 39 is connected by the bail 40 75 to the apex of the member 37, while the lower end thereof is mounted within the securing member 41 to the upper portion of the platform 4.

The cable 36 is connected to the winding 80 drum 42, which is fixed upon a shaft 43 journaled between the supports or standards 3, said shaft having fixed upon one end adjacent the shaft 14, the gear 44, which meshes with the worm 45 carried by the 85 shaft 14. It will thus be seen that as the shaft 14 is operated to impart rotation to the shaft 7, that a slow motion will be imparted to the drum 42 to permit of the gradual lowering of the shaft 7 and the auger 90 member carried thereby. Thus as the auger member is rotated to cut the earth, the shaft will be lowered in timed relation thereto.

A reverse operation of the shaft 14 will cause the elevation of the shaft 7 and thus 95 permit the auger member to be elevated from the bore.

What is claimed is:

In a machine of the character described, the combination of a supporting structure, 100 a vertically slideable rotary shaft, means for rotating the shaft, a receptacle carried by the lower end of the shaft to cut and hold the dirt, two pairs of outstanding arms attached to the shaft, one pair within the receptacle and the other pair above the same, sprocket wheels mounted for rotation upon said arms, endless sprocket chains trained over said sprocket wheels and having buckets, bevel gears carried by the upper 110 sprocket wheels, and a stationary bevel gear carried by the supporting structure and meshing with the aforesaid bevel gears, whereby when said shaft is rotated, the sprocket chain is operated, the receptacle 115 having a central depending auger and slots extending radially from the auger between the lower sprocket wheels.

In testimony that I claim the foregoing as my own, I have hereto affixed my signature 120 in the presence of two witnesses.

NATHAN T. HARMON.
